(No Model.)

E. W. WHITTAKER.
TENNIS BELT.

No. 450,050.

Patented Apr. 7, 1891.

UNITED STATES PATENT OFFICE.

EDWARD W. WHITTAKER, OF NEW YORK, N. Y.

TENNIS-BELT.

SPECIFICATION forming part of Letters Patent No. 450,050, dated April 7, 1891.

Application filed December 10, 1890. Serial No. 374,232. (No model.)

To all whom it may concern:

Be it known that I, EDWARD W. WHITTAKER, a citizen of the United States, residing at New York, in the county and State of New York, have invented certain new and useful Improvements in Tennis-Belts, of which the following is a specification.

I have had in view the production of a belt made of a broad smooth band of satin, as distinguished from the plaited and folded tennis-sashes heretofore in use.

I will first describe my invention with reference to the accompanying drawings, and will point out in the claims the novelty of the invention.

In said drawings, Figure I represents in perspective my improved tennis-belt. Fig. II is a side view of the same in one form, and Fig. III a similar view, partly broken away, in another form. Fig. IV is a sectional view through the clasp shown in Fig. III. Fig. V is a detail view of the safety-pin.

1 is a broad, flat, smooth central band of satin or other suitable material. This main part is, say, four inches wide; but its ends are slightly tapering and narrowed, as shown at 2, to enter and be attached to elongated rings 3, which have vertical spreaders at 4 for strengthening them.

5 5 are straps of leather tapering and fixed to the rings 3 at their larger ends and adapted to be united at their smaller ends and adjusted by the clasp now to be described.

6 is the front or main body of the clasp, having a rectangular yoke 7, to which one strap 5 is attached. To the inner side of the front 6, pivoted in its top and bottom flanges 8, is a cam-shaped clamp 9, between which and the front 6 the other strap 5 is attached 40 to be passed and clamped. A sliding keeper 10 holds the ends of the last-named strap to position.

Another form of attachment is shown in Fig. IV. Here the clasp has two bodies 6 6^a,

united by hook 11 and eye 12, each having 45 the pivot-clamp 9, so that both straps 5 may be adjusted, and thus extend considerably the scope of the belt. In this form the keeper 10 may retain both of the loose ends of the straps. The broad portion of the belt is in 50 front of the wearer's body when in use. These belts are sometimes inconvenient, as they are apt to rise above the trousers of the wearer, and I have therefore devised means for holding them down over the top of the trousers. 55 To this end I sew or otherwise attach on the inside of the front portion of the belt a narrow vertical tape 13, to which I fix a safety-pin 14, having an arm secured to the middle portion of the tape. When the belt is in place, 60 the safety-pin can be attached to the trousers, and the belt is thereby held securely in position. In a broad band of this sort I find it desirable to use the rings 3, which allow the movements of the wearer's body without 65 creasing the band 1.

Having thus described my invention, the following is what I claim as new therein and desire to secure by Letters Patent:

1. A tennis-belt having a broad central 70 band, end straps provided with suitable fastening, and the elongated rings within which the adjacent ends of the band and straps are fixed, the rings permitting the movement of the wearer's body without the liability of 75 creasing the band, substantially as described.

2. A tennis-belt having a broad smooth central band, end straps provided with suitable fastening and connected with the ends of the band, the vertical tape extending across 80 the band, and a safety-pin having an arm secured to the middle portion of the tape, substantially as described.

E. W. WHITTAKER.
